UNITED STATES PATENT OFFICE.

JOHN E. McMULLEN, OF COUNCIL BLUFFS, IOWA.

DOOR LATCH.

Application filed August 7, 1924. Serial No. 730,780.

To all whom it may concern:

Be it known that I, JOHN E. McMULLEN, a citizen of the United States, residing at Council Bluffs, in the county of Pottawattamie and State of Iowa, have invented a new and useful Improvement in Door Latches, of which the following is a specification.

My invention relates to latches adapted to hold a door both open and closed; and the objects of my improvement are, first, to provide a latch easily adapted to control the movement of opening and closing a door; second, to provide such a latch that will hold the door locked both in an open and closed position; and, third, to provide such a latch that will be simple in construction and operation.

I attain these objects by the device and structure illustrated in the accompanying drawing, in which—

Figure 1 is a side elevation of a door with latch attached; Fig. 2 is a cross section of a latch and latch lock; Fig. 3, is a plan of the door and attachment; Fig. 4 is a side elevation of the latch catch; Fig. 5 is a front elevation of the latch catch; Fig. 6 is a side elevation of another form of the latch catch; Fig. 7 is a side elevation of the latch showing its operation through the door to the outside; Fig. 8 is a side elevation of a locking device; and Figure 9 is an end elevation of the locking device shown in Figure 8.

Similar numerals refer to similar parts throughout the several views.

d is any ordinary door such as is used on barns or garages; *j* is the door frame. This door is hinged at *a*; a brace *b* is pinned at *c*; a latch rod *p* has an arm *m* adapted to turn in approximately 180 degrees on the side of the door *d*; a second lever portion *n* of the latch rod *p* and substantially parallel with the arm *m* engages the brace *b* at its extremity from its pivot at *c*, and at the point *e* in said brace *b*. When the lever arm *m* of the latch rod *p* is turned to a position as to the right against the door *d*, the lever *n* of the latch rod *p* draws the brace *b* against the pivot *c* to hold the door closed. By moving the lever arm *m* of the latch rod *p* in the opposite direction, as to the left of the door *d*, the door will be moved about its hinges *a* away from the pivot *c* to open. When the lever *m* has reached a position approximately

180 degrees, or to the face of the door against which the latch rod *p* is hinged, the lever *m* will assume a position parallel to the door and the brace *b* will extend from its pivot *c* to its engagement at *e* with the lever *m* and will brace and hold open the door *d* so long as the lever *m* remains parallel with the door *d*. Catches *f* and *f'* are adapted to catch and hold the lever *m* when turned towards the free end of the door and when turned in the opposite direction. When the lever *m* is brought within the catch *f* towards the free end of the door *d*, the door will be drawn closed and so held by the brace *b*. When the lever *m* is turned to engage the catch *f'*, the door *d* will be held braced open by the brace *b*. The catch *f* may extend through the door or not, as may be desired; and when the said catch *f* so extends through, as shown in Figure 4, a pawl *q* may be arranged to lock the catch *f* so that it can only be opened from the inside.

To hold the door tightly shut the catch as shown in Figures 8 and 9 is employed. A catch *o* is pivoted in the support *r* on the door. A loop *f''* is provided to receive the catch *o* so that when the door is shut the catch falls over the loop *f''* when the handle *m* is in the slot *f* as shown in Figure 1. To open the door the lever *m* is raised, when it impinges against the catch *o* lifting it in the loop *f''* allowing the door to open freely. Catches *f'''* and *f''''* may be used as shown in Figure 6 instead of a rotary form, as used in Figure 4, and a latch may be introduced through the door to lift the lever *m* of the bar *p* to operate the lock. When it is desirable to lift the latch *f* from the outside, a form of latch may be used as in Figure 2.

While locks using braces to hold doors open and shut have been used heretofore, what I claim and desire to claim by Letters Patent is:

1. In a door latch a locking brace pinned at a point remote from the door hinge on the door frame, a latch rod hinged on the door adapted to rotate through half a circle, a lever portion thereon adapted to serve as a handle, and a second lever portion thereon engaging the free end of said brace.

2. In a door latch, a locking brace pinned at a point on the door frame remote from the door hinge, a latch rod hinged

on the door having a lever portion and another portion parallel with the said lever portion engaging the free end of the said brace, the said lever portion and portion 5 engaging the free end of said brace being adapted to rotate through half a circle, catches to hold the said lever portion of said latch rod in its rotation on the door, and a catch to hold said door shut and 10 adapted to be operated by said latch rod when lifting it out of its catches on the door.

3. In a door latch, a locking brace pinned at a point remote from the door hinge

on the door frame, a latch rod hinged on 15 the door adapted to rotate through half a circle, a lever portion thereon adapted to serve as a handle, a second lever portion thereon engaging the free end of said brace, catches adapted to engage and hold the end 20 lever arm of said latch rod, and said latch rod having an end movement allowing the said latch rod to engage said catches and one or more of said catches adapted to be operated from the outside of said door and 25 a pawl to lock the said catch against operation from the outside.

JOHN E. McMULLEN.
